(57) **CLAIM**

The ornamental design for a baby bouncer seat, as shown and described.

DESCRIPTION

FIG. 1 is a top, front, right side perspective view of a baby bouncer seat showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right side perspective view showing the baby bouncer seat in an alternate position;

FIG. 9 is a top, front, right side perspective view of the baby bouncer seat, shown in a first condition of use;

FIG. 10 is a top, front, right side perspective view of the baby bouncer seat, shown in a second condition of use; and,

FIG. 11 is a top, front, right side perspective view of the baby bouncer seat, shown in a third condition of use.

The deemphasized lightened portions surrounded by broken lines and the broken lines representing the boundary are for environmental and illustrative purposes only and form no part of the claim.

1 Claim, 11 Drawing Sheets
